UNITED STATES PATENT OFFICE.

HOWARD L. ELTON, OF PHILADELPHIA, PENNSYLVANIA.

CONCENTRATOR.

SPECIFICATION forming part of Letters Patent No. 591,335, dated October 5, 1897.

Application filed August 29, 1896. Serial No. 604,253. (No model.)

To all whom it may concern:

Be it known that I, HOWARD L. ELTON, a citizen of the United States, residing at Philadelphia, in the county of Philadelphia and 5 State of Pennsylvania, have invented certain new and useful Improvements in Concentrators; and I do hereby declare the following to be a full, clear, and exact description of the invention, such as will enable others skilled 10 in the art to which it appertains to make and use the same.

This invention has reference to a novel construction in an ore-concentrator; and it consists in features of construction hereinafter 15 described and claimed.

In the accompanying drawings, illustrating this invention, Figure 1 is a central vertical section, and Fig. 2 is a top plan view.

Referring to said drawings, 1 indicates a 20 casing, preferably cylindrical and having a cone-shaped lower end. This casing is closed, and its top piece is provided with a central opening 2, a water-supply pipe 3, and an ore-supply pipe 4, preferably leading from a hopper 25 per 5 and having a valve 6. The water-supply pipe 3 is also provided with a valve 7. The lower end of the casing 1 terminates in a pipe 8, which is provided with two valves, one valve, 9, being situated adjacent to the 30 lower end of the casing and the other, 10, at the lower end portion of this pipe 8.

Passing through the opening 2 in the center of the casing is a rotatable cylinder 11, closed at its lower end and provided thereat 35 with a valve 12 and resting at its lower end in a supporting-bearing 13. The upper end portion of this cylinder projects through an opening 2 and through a suitable bearing 14 on the top piece of the casing, while its upper end opens into a pan 15, from which a trough 16 extends. Between the opening 17 and the bearing 14 the cylinder is provided 40 with any efficient means for rotating the same, which may be a pulley 18, as shown in Fig. 1.

Within the casing and secured to the cylinder 11 is an agitator 19, which rotates with said cylinder and can be of any approved construction, but which we have illustrated as 45 consisting of a spirally-inclined plane on the principle of an Archimedean screw. When 50 this spiral agitator 19 is employed, it is de-

sirable to form an upturned flange 20 at its periphery. The sides of the cylinder, between the plates of the agitator, are perforated, as at 20^a, so that the water and suspended ore 55 can pass from the casing into this cylinder.

I also provide receptacles for holding mercury to extract the ore that is held in suspension by the water, and these receptacles can be situated either in the pan, trough, or 60 within the cylinder 1. We have shown in the drawings a series of cups or channels 21 on the inner face of the cylinder, a bowl 22 suspended from the upper end of the cylinder, and a series of transverse grooves 23 in the 65 trough, which act as riffles.

The parts being constructed and arranged as described, the operation is as follows: The valves 6 and 9 are closed, and the valve 7 is opened to allow the water to fill the casing 1, 70 after which it is closed. The cylinder and agitator are then rotated, and then the valve 6 is opened to admit the crushed ore, which is supplied until it reaches the point of precipitation. The valve 7 is then opened 75 slightly, and the pressure of the water and the admission of the ore will expel the water through the openings 20^a and the cylinder 11. The water rises slowly in the cylinder until it runs over the top, carrying with it the 80 lighter particles of the ore, the larger pieces and all particles that are not held in suspension by the water falling to the bottom of the casing, from which they can be removed by means of valves 9 and 10. Should pieces 85 of ore, however, too large to be held in suspension by the water find their way through the opening 20^a into the cylinders, they will be precipitated to the bottom of the cylinder, in which the water is not agitated, but is 90 nearly quiet and rising slowly. The particles thus dropping to the bottom of the cylinder 11 can be removed by means of the valve 12. The ore held in suspension by the water in passing over the receptacle containing the 95 mercury will be taken up by this chemical in an obvious manner, thus extracting from the water such particles as may escape the mechanical action.

Having thus described my invention, what 100 I claim as new, and desire to secure by Letters Patent, is—

1. In an ore-concentrator, a casing having a water-inlet, an ore-inlet, an outlet at the lower end of said casing, valves controlling said inlets and outlet, a rotatable hollow cylinder situated within said casing having a closed lower end provided with a valve, the upper end portion of said cylinder extending through the top of the casing and leading to an outlet, openings in the sides of said cylinder, and an agitator carried by said cylinder, substantially as described.

2. In an ore-concentrator, a casing having a water-inlet, an ore-inlet, an outlet at the lower end of said casing, valves controlling said inlets and outlet, a rotatable cylinder situated within said casing and communicating therewith and provided with an agitator, receptacles situated within said cylinder for the reception of chemicals, and the upper end portion of said cylinder communicating

with an inclined pan, substantially as described.

3. In an ore-concentrator, a casing having a water-inlet, an ore-inlet, an outlet at the lower end of said casing, valves controlling said inlets and outlet, a rotatable cylinder situated within said casing and provided with an agitator comprising a spirally-arranged plate, openings in the sides of said cylinder between the convolutions of the spiral, and a suitable outlet at the upper end of said cylinder, substantially as described.

In testimony whereof I have signed this specification in the presence of two subscribing witnesses.

HOWARD L. ELTON.
